UNITED STATES PATENT OFFICE.

HENRY H. COLLINS, JR., OF PHILADELPHIA, PENNSYLVANIA, ASSIGNOR
TO A. M. COLLINS MANUFACTURING COMPANY, OF PHILADELPHIA, PENNSYLVANIA, A CORPORATION OF PENNSYLVANIA.

DESIGN FOR A PHOTOGRAPHIC CARD-MOUNT.

SPECIFICATION forming part of Design No. 37,307, dated January 31, 1905.

Application filed December 5, 1904. Serial No. 235,639. Term of patent 7 years.

To all whom it may concern:

Be it known that I, HENRY H. COLLINS, JR., a citizen of the United States, residing in Philadelphia, Pennsylvania, have invented a new, 5 original, and ornamental Design for a Photograph Card-Mount, of which the following is a specification.

In the accompanying drawings, Figure 1 is a face view of a photograph card-mount showing my new design; and Fig. 2 is an enlarged section of the same on the line a a, Fig. 1.

What I claim, and desire to secure by Letters Patent, is—

The ornamental design for a photograph card-mount, as shown.
